UNITED STATES PATENT OFFICE.

WILLIAM ARMSTRONG, OF MARTINSBURG, WEST VIRGINIA, ASSIGNOR TO
JOHN FITZ AND JOHN FARRIN, OF SAME PLACE, ONE-THIRD TO EACH.

HAND SIGNAL-LANTERN.

SPECIFICATION forming part of Letters Patent No. 224,065, dated February 3, 1880.

Application filed October 10, 1879.

To all whom it may concern:

Be it known that I, WILLIAM ARMSTRONG, of Martinsburg, in the county of Berkeley and State of West Virginia, have invented 5 certain Improvements in Hand Signal-Lanterns, of which the following is a specification; and I do hereby declare that in the same is contained a full, clear, and exact description of my said invention, reference being had to the accompanying drawings, and to the letters of reference marked thereon.

This invention relates to a hand-lantern in which a colored-glass plate is attached thereto, through which a colored light may be displayed as a signal on railroads or shipping, or 15 for other uses.

The said invention consists, first, in combining with the burner a frame-work of particular construction and a detachable colored-glass plate fitting therein; and, secondly, in 20 combining with the burner, frame, and detachable glass plate a wick-tube extended to near the bottom of the lantern, to prevent extinguishment of the flame in swinging the lantern, as is practiced in the act of signaling.

In the drawings forming a part hereof, Figures I and II represent a part of a lamp embodying my improvements as seen from different points of view. Fig. III illustrates a 25 modified form of the invention.

Similar letters of reference indicate similar parts in both views.

In Figs. I and II the burner A is provided with a bracket, a, inserted in a slot cut in the burner, and bent over, as shown. The outer end of the bracket is riveted to a signal-support, b, having sides b', bent V-shaped to receive the colored-glass signal-plate c. The sides b' are bent somewhat inward from a vertical line in order to exert a slight pressure upon the edges of the glass and hold it in position. The glass is readily removed from the support b.

It will be observed that the burner shown 45 in Figs. I and II is of that construction in which the wick is raised within the wick-tube B by means of a feed-wheel.

In Fig. III is shown a well-known form of

burner, in which the wick is raised by the use of a pointed tool inserted through slots cut in 50 the wick-tube. In adapting my invention to this class of burners I provide a disk, d, slotted at e to fit over the upper part of the wick-tube, to which disk is riveted the bracket a, carrying the signal-support b, as before de- 55 scribed.

The colored glass is sufficiently far removed from the flame to be untouched by it, but will permit a colored light to be distinctly shown 60 when desired.

Glass plates of different colors may accompany each lantern, to be used in different kinds of signaling.

The wick-tube B in all cases extends to near the bottom of the illuminating-fluid, or 65 to a point so near to the bottom of the oil-chamber of the lamp as to give sufficient space only for the wick to extend from the tube. By this means the oil in contact with the wick is not agitated in swinging the lamp in 70 the act of signaling, as will be readily understood.

Such a construction is necessary, more particularly by reason of the close proximity of the flame to the glass plate, as any flickering 75 of the flame would smoke the glass and render it unfit for signaling purposes.

I am aware that in signal-lamps in which the glass plates are outside of the body of the lantern and wholly removed from danger 80 of becoming smoked by the flame the wick-tube has been carried down to near the bottom of the oil-reservoir, and such a wick-tube, therefore, I do not claim, except in combination with other features entering into my in- 85 vention.

I am aware, further, that heretofore a signal-plate held in a frame has been applied to a signal-lamp burner, the frame being removable. This differs from my invention in that 90 in my lamp the frame is stationary, or secured to the burner, and the glass or glasses are slipped into the frame, being thereby changed as required, one frame answering for the glasses of various colors, which simplifies the device. 95 I therefore do not wish to claim a lamp hav-

ing a glass signal-plate rigidly held in a frame, the latter being made removable from the burner; but,

Having described my improvements, I claim
5 as my invention—

1. In combination with the burner A, bracket
a, and signal-support b b', the detachable glass
plate c, substantially as specified.

2. The burner A, having the wick-tube B,

extended downward, as described, combined or
with the bracket a, signal-support b b', and
detachable glass plate c, substantially as set
forth.

WILLIAM ARMSTRONG.
